2,240,002

COLLAR AND NECKTIE SUPPORT

Donald P. Killen, Glendale, Calif.

Application June 19, 1939, Serial No. 279,923

1 Claim. (Cl. 2—132)

My invention relates to a collar and necktie support and has for its principal object, the provision of a relatively simple, practical and inexpensive device that is adapted to engage and maintain in proper position and relation, the depending points on the forward ends of a collar, particularly the soft, finished collars now in general use and also, the knotted portion of the necktie that is associated with the collar and which extends downwardly from the pointed forward ends thereof.

A further object of my invention is, to provide a device of the character referred to which, in addition to maintaining the pointed forward portions of a soft, folded collar in proper position, will engage and exert forward pressure on the knotted portion of the tie so as to force the same forwardly to a position in front of the pointed ends of the collar, thus adding materially to the appearance and dressed effect of the collar and tie.

A further object of my invention is, to provide a collar and necktie support capable of being easily and quickly applied to or removed from a collar and tie and further, to construct the device so that when in use it is entirely hid from view.

With the foregoing and other objects in view, my invention consists in certain novel features of construction and arrangement of parts that will be hereinafter more fully described and claimed and illustrated in the accompanying drawing in which:

Fig. 1 is a perspective view of a collar and tie with dotted lines showing my improved support applied thereto.

Fig. 2 is a perspective view of the combined collar and tie holder.

Fig. 3 is a perspective view partly in section and showing the holder in position upon a collar and tie and said view being taken looking against the inner faces of the depending points of the collar and against the inner face of the knotted portion of the tie.

Fig. 4 is a vertical section taken on the line 4—4 of Fig. 2.

Fig. 5 is a perspective view of a modified form of the collar and tie holder.

Referring by numerals to the accompanying drawing which illustrates a preferred embodiment of my invention, 10 designates a narrow strip of thin, flexible and, more or less resilient material, for instance, metal, and both ends of this strip are rounded as designated by 11.

Depending from the lower edge of the strip 10 adjacent its ends are pin-like legs 12 of re-

silient material, preferably metal, the lower portions of which are bent to form loops 13 and, the ends of said loops terminate in downwardly presented points 14.

Secured to or formed integral with the strip 10, preferably at a point midway between the legs 12, is a pin-like member 15 that is substantially shorter than the members 12 and, the lower portion of this member 15 is formed into a loop 16 and the end thereof terminates in a depending pin 17. Member 15 is inclined with respect to the plane occupied by the members 12 and thus, the looped pointed lower end of said member 15 occupies a position a substantial distance in front of the vertical plane occupied by the members 12 as seen in Fig. 4.

When my improved collar and tie holder is applied for use, the thin, flexible strip 10 is inserted in the upper central portion of the folded collar, beneath the tie and, the members 12 extend downwardly against the inner faces of the pointed forward ends of the collar with the points 14 at the lower ends of said members engaged through the lining or inner layer of material forming the collar and thus, the pointed ends of the collar are maintained in practically flat positions against the collar band and the underlying portions of the shirt.

The member 15 extends downwardly directly behind the knotted portion of the tie with the point engaged in the fabric in the rear portion of the tie as illustrated in Fig. 3 and, due to the inclined position of member 15 it will press and thereby force the knotted portion of the tie forwardly between the pointed ends of the collar, thereby attaining the desired results and imparting to the pointed ends of the collar and the knotted portion of the tie an attractive and well-dressed appearance.

As illustrated in Figs. 2 and 3, I prefer to cut away the intermediate portion of the resilient member 10 along the upper edge thereof as designated by 10a, in order that the end portions of said strip are slightly wider than said intermediate portion inasmuch as such construction enables the wider end portions to bear directly against the folded edge of the collar. This arrangement maintains the holder in stable position while in use and effectually prevents tendency of the member 10 to tilt or fulcrum at a central point on the front ends of the collar as one side or the other thereof is depressed by sidewise movements of the wearer's head.

The modified construction illustrated in Fig. 5 includes a narrow strip 18 of resilient material

similar to strip 10 and, the pin-like legs 19 that depend from said strip 18 are wound with a single layer of fine, resilient wire 20 and, which construction adds materially to the resiliency of the collar supporting members 19.

In the modified construction, the intermediate forwardly projecting inclined member 21, similar to member 15, is wound with a single layer of fine, resilient wire 22, thus increasing the resiliency of the tie supporting part of the holder.

Thus it will be seen that I have provided a collar and tie holder that is relatively simple in construction, inexpensive of manufacture and very effective in performing the functions for which it is intended.

It will be understood that minor changes in the size, form and construction of the various parts of my improved collar and necktie support, may be made and substituted for those herein shown and described, without departing from 20

the spirit of my invention, the scope of which is set forth in the appended claim.

I claim as my invention:

5 A collar and necktie support formed from a single piece of material and comprising a strip of thin, resilient material, collar supporting members depending from said strip adjacent its ends, the lower portions of which collar engaging members are bent to form open loops, the ends thereof terminating in depending points, a resilient tie engaging member extending downwardly and forwardly from the intermediate portion of said resilient strip which tie engaging member is shorter than the collar supporting members, the lower portion of which tie engaging member is bent to form an open loop and the end of said loop terminating in a depending point.

10 15 20 DONALD P. KILLEEN.
